(57) **CLAIM**

The ornamental design for a camera assembly of a video communication set, substantially as shown and described.

DESCRIPTION

FIG. 1 is a perspective view of a camera assembly of a video communication set showing our new design.

FIG. 2 is a front view of the camera assembly of the video communication set of FIG. 1.

FIG. 3 is a back view of the camera assembly of the video communication set of FIG. 1.

FIG. 4 is a left side view of the camera assembly of the video communication set of FIG. 1.

FIG. 5 is a right side view of the camera assembly of the video communication set of FIG. 1.

FIG. 6 is a top view of the camera assembly of the video communication set of FIG. 1; and,

FIG. 7 is a bottom view of the camera assembly of the video communication set of FIG. 1.

The broken lines in the drawings consisting of uniform large dashes showing a connecting cord depict environment only and form no part of the claimed design; the broken lines consisting of a long dash and two short dashes depict portions of the camera assembly of a video communication set that form no part of the claim.

1 Claim, 4 Drawing Sheets
